UNITED STATES PATENT OFFICE.

HERMANN SEEWALD, OF PÖSSNECK, GERMANY.

ELECTRIC LOCK.

SPECIFICATION forming part of Letters Patent No. 689,133, dated December 17, 1901.

Application filed April 24, 1901. Serial No. 57,310. (No model.)

To all whom it may concern:

Be it known that I, HERMANN SEEWALD, a citizen of Germany, residing at Pössneck, in the Duchy of Saxe-Meiningen, Germany, have 5 invented certain new and useful Improvements in Locks Set in Motion by Electricity; and I do hereby declare the following to be a full, clear, and exact description of the invention, such as will enable others skilled in the 10 art to which it appertains to make and use the same.

This invention relates to electric locks for safes, treasuries, or the like, the object being 15 to provide an improved lock of this class having a frame provided with a rack in which is arranged a movable bolt moved forward and backward by means of a toothed wheel set in motion by a watch-spring and a crank after an electric current has detached several 20 anchor-holds through the setting in of different contacts, whereby it is only possible to open the lock when one has access to the contacts arranged at various places and understands their mode of action.

25 With this object in view the invention consists in the improved construction, arrangement, and combination of parts hereinafter fully described and afterward specifically claimed.

30 The drawings appended hereto represent such a lock.

Figure 1 shows the same diagrammatically in a closed position, and Fig. 2 in an open position. Fig. 3 represents, in elevation, the 35 frame with the bolt and appurtenances. Fig. 4 is a plan of the parts shown in Fig. 3. Fig. 5 shows, on an enlarged scale, one form of contact device. Fig. 6 is a sectional view of the same. Fig. 7 shows the lock ready for 40 use, the case being partly in section and partly broken away.

The toothed wheel *d*, set in motion by a watch-spring *a* and capable of being held stationary by a sliding pawl *b* catching in the 45 notch *c'* of a disk *c*, turns around the arbor *d'* and engages the rack *e'* of the frame *e*, said rack being shown in dotted lines. In the frame *e* there is a bolt *f*, so arranged as to be movable by means of the guide-rod *f'''*, provided with a spring *f''*, the bolt having a keeper *f'*. The armature *g* of the magnet *A*

keeps back the contact-slide *h* communicating with the positive conducting-wire 2 of the magnet *B*, said slide being provided with a spring *h'*, by which it is held normally against 55 the contact-piece *i*, with which the wire 1 is connected. The pin *h''* serves for drawing back the slide if the contact has been closed. The negative conducting-wire 3 of the magnet *B* extends to the battery and forms, if the 60 current is closed, with wires 1 and 2 a circuit. The slide *b*, which is provided with a pin *b'* for drawing it back to its former place after being detached, is held by armatures *k* and *l* of the magnets *B* and *C*. The armature *l* is 65 held fast in its released state by a latch *l'''*, pivoted on a pin *l''*, said latch being detached again by means of the pin *l'*. By the wires 4 and 5 the magnet *C* communicates with the contact *m''*, which moves over the insulating- 70 ring *m* of the watch *m'*. The pawl-lever *n'*, placed in the horizontal plane and pivoted on pin *n*, serves to detach bolt *f*, which is held fast by latch *o*, provided with a pin *o'* and a spring *o''*, as well as by armature *p* of the 75 magnet *D* of the other fold or wall. By wires 6 and 7 the magnet *D* is to be put in communication with the source of the current.

The mechanical effect of the lock is the following: When by connection of the wires 8 80 and 9 a circuit is completed and the magnet *A* is energized, and thus the armature *g* is attracted and the slide *h* moves to contact with the contact *i*, the circuit is closed by wires 4 and 5 of the magnet *C* through the medium 85 of the watch-contact, which only operates at the time fixed through the hole *q* in the insulating-ring, whereby the armature *l* is held fast by the latch *l'''*. By connection of the 90 conducting-wires 1 and 3 the armature of the magnet *B* is attracted and the released slide *b* is drawn back by the spring *b''*, so that the turning back of the frame *e* with the slide *f* is only prevented by armature *p* of the magnet *D*. If the circuit of this magnet is now 95 closed by the connection of the wires 6 and 7, then the armature *p* is attracted and the frame *e*, with the bolt *f*, is turned back by the watch-spring *a* and the toothed wheel *d* and the lock is now opened, whereby the keeper 100 *f'* of the bolt *f* is placed behind the pawl-lever *n'*. If it is intended to now close the

lock again, then the latch *o* is lifted out with the aid of the pin *o'* and the frame *e* is turned back to its old place by a crank fixed to the arbor *d'*, whereby the spring *f''* is 5 pressed together, inasmuch as the pawl-lever *n'* keeps back the bolt *f*. By means of the pin *b'* the slide *b* is now thrown back again in the notch *c'* of the disk *c*, and the armatures *k* and *l* catch in again after the latch *l'''* has 10 been detached by pin *l'*. The hand of the watch-contact has meanwhile moved further on and the current is interrupted again, so that it yet needs only a drawing back of the slide *h* by the pin *h''*. If this is also done, 15 the door can be shut again, at which the pawl-lever *n'* is shoved aside and now sets free the bolt *f*, so that the latter is drawn to the fore part by spring *f''* and is again held

fast by armature *p*. To open the lock again, the proceeding described must be repeated. 20

Having thus described my invention, what I claim as new, and desire to secure by Letters Patent of the United States, is—

An electric lock provided with a bolt *f*, a frame *e* and toothed wheel *d*, for setting it in motion, electromagnets *A*, *B*, *C* and *D* having armatures for preventing the withdrawal of the bolt, and a watch-contact whereby the circuits of the magnets are broken to release the armatures, substantially as described. 25 30

In testimony whereof I affix my signature in presence of two witnesses.

HERMANN SEEWALD.
